UNITED STATES PATENT OFFICE.

CHARLES H. HUTTO, OF HOUSTON, TEXAS, ASSIGNOR, BY MESNE ASSIGNMENTS, OF ONE-HALF TO ANNA LOU MILNER, OF PINE BLUFF, ARKANSAS.

PIPE PULLER.

Application filed March 30, 1923, Serial No. 628,813. Renewed May 21, 1925.

To all whom it may concern:

Be it known that I, CHARLES H. HUTTO, a citizen of the United States, residing at Houston, in the county of Harris and State 5 of Texas, have invented certain new and useful Improvements in Pipe Pullers, of which the following is a specification.

This invention relates to a grapple or puller, designed primarily for removing 10 well casing sections, tubes and pipes which have been sunk or embedded in the ground, from such position, but it is to be understood that a grapple or puller, in accordance with this invention, can be employed 15 for any purpose wherein it is found applicable, and the invention has for its object to provide a device of such class, in a manner as hereinafter set forth, with a pair 20 of gripper elements, one shiftable lengthwise relatively to the other, and means cooperating with said gripper elements, when one is shifted relatively to the other for causing said elements to be moved into and held in gripping engagement with respect 25 to the casing section, pipe or tube, whereby when the grapple is elevated the casing section, pipe or tube will be carried therewith.

Further objects of the invention are to 30 provide a device, for the purpose set forth and in a manner as hereinafter more fully described, which is simple in its construction and arrangement, strong, durable, compact, thoroughly efficient in its use, conveniently operated for clamping the article 35 to be drawn or lifted, readily installed and comparatively inexpensive to manufacture.

With the foregoing and other objects in view, the invention consists of the novel construction, combination and arrangement 40 of parts, as hereinafter more specifically described and illustrated in the accompanying drawings, wherein is shown an embodiment of the invention, but it is to be understood that changes, variations and modifications can be resorted to which come within the scope of the claims hereunto appended.

In the drawings wherein like reference 50 characters denote corresponding parts throughout the several views:—

Figure 1 is a front elevation of a grapple or puller, in accordance with this invention, with the elements of the device in non-clamping position.

Figure 2 is a side elevation with the ele-

ments of the device in non-clamping position.

Figure 3 is a vertical sectional view of the grapple or puller, with the gripper elements in non-gripping position and further 60 illustrating the position of the device with respect to a pipe, the latter being shown in dotted lines.

Figure 4 is a view similar to Figure 3 with the gripper elements of the grapple or puller 65 shifted to gripping position with respect to the pipe.

Figure 5 is an elevation of the shiftable gripper element of the grapple or puller.

Figure 6 is a view similar to Figure 5 of 70 the other gripper element of the grapple or puller.

Figure 7 is a section on line 7—7, Figure 3.

Figure 8 is a section on line 8—8, Figure 3.

Figure 9 is a section on line 9—9, Figure 3. 75

Figure 10 is a perspective view of the shifting member cooperating with the clamping elements for shifting them laterally with respect to each other to clamping position with respect to the pipe.

Figure 11 is a sectional elevation of a modified form of grapple or puller, in accordance with this invention.

Figure 12 is a fragmentary view of the shiftable clamping elements of the form 80 shown in Figure 11.

Figure 13 is a section on line 13—13, Figure 11.

Referring to Figures 1 to 10 of the drawings, a grapple, puller or lifting device, in 90 accordance with this invention, which is hereinafter termed a pipe puller, comprises a shiftable gripper element, a gripper element constituting a carrier for the other gripper element, a plurality of shifting members interposed between and cooperating with the gripper elements for shifting them laterally relative to each other whereby they are moved to gripping position to grip the pipe for lifting the same, a spring controlled 95 connecting element for detachably connecting the gripper elements together, and a lifting element for each of the gripper elements.

One of the gripper elements, is indicated generally by the reference character 10, and 100 the other of the gripper elements is indicated generally by the reference character 11.

The gripper element 10 constitutes a carrier for the gripper element 11, and said gripper element 10 consists of an interme- 110

diate portion 12, which is semi-circular in cross section, and said element 10 further includes an upper portion 13 which is semi-circular in cross section and tapers from its lower to its upper terminus. The element 10 further includes a lower portion 14, which is cylindrical in cross section and formed with a tapered lower end 15. The lower portion 14 is provided with a tapered socket 16, which is segment shaped in contour, and the size of the mouth of the socket 16 is such as to provide at the upper end of the lower portion 14, a segmental shoulder 17.

15 The top of the upper portion 13 is formed with a socket 18, in which is secured the shank 19 of a threaded member 20, extending above the upper terminus of the element 10 and which provides means for securing 20 a lifting element to the upper end of the element 10 and which will be hereinafter referred to.

25 The inner face of the element 10, at the upper end of the intermediate portion 12, and further at a point in proximity to the lower end of said intermediate portion 12, is formed with a cavity, and one of said cavities is indicated at 21 and the other at 22. The bottom wall 23, of each of said 30 cavities is flat, and the inner wall which is indicated at 24, extends upwardly from the inner end of the wall 23, and at an outward inclination, whereby a cavity is set up having its inner wall 24 constituting a wedge 35 actuating means. Each of the cavities are of triangular contour.

40 The intermediate portion 12, of the element 10, between the cavities 21 and 22, is provided with a chamber 25, which opens at the inner face of the element 10, through 45 the medium of a lengthwise extending elongated rectangular slot 26. The outer face of the element 10, is provided with an opening 27, communicating with the chamber 25 and which provides means for the positioning in the chamber 25 of a spring controlled connecting member which will be presently referred to.

50 The element 11 is semi-circular in contour at any point throughout its length, and includes an intermediate portion 28, a lower portion 29 and an upper portion 30. The lower portion 29 is tapered and is inset with respect to the intermediate portion 28, and said lower portion 29 provides a retaining projection which seats in the socket 16 when the elements 10 and 11 are engaged together in a manner as hereinafter referred to. The socket 16 acts as a retaining means for 55 the lower portion 29 and also performs somewhat the function of a guide during the lengthwise shifting of the element 11 relative to the element 10.

60 The upper portion 30 of the element 11 tapers from its lower to its upper terminus,

and at its upper end is formed with a socket 31, in which is secured the shank 32, of a threaded member 33, which projects upwardly from the top of the portion 30 and is adapted to have secured therewith, in a 70 manner to be presently referred to, a lifting element.

75 The inner face of the intermediate portion 28, of the member 11, is provided near its upper end and in proximity to its lower end with a wedge shaped cavity, and the said cavities are indicated at 34, 35, and are similar in construction to the cavities 21, 22. The cavity 34 opposes the cavity 21 but is oppositely disposed with respect 80 thereto. The cavity 35 opposes the cavity 22 but is oppositely disposed with respect thereto. The inner walls of the cavities 34, 35, are indicated at 36 and provide wedge shifting means.

85 The shifting members for the gripper elements, are each formed of a short cylindrical roller 37, one of which is mounted in the cavities 21, 34, and the other of which is mounted in the cavities 22, 35. The shafting members are engaged by the inner walls 24, 36, of the cavities, so that when the element 11 is moved upwardly relative to the element 10, the members 37 engaging the inclined walls 24, 36, will shift the elements 90 10 and 11 laterally to a position to grip the inner face of the pipe 38, and when moved to such position, when the gripper elements are simultaneously elevated the pipe 38 will be carried therewith. The position to which 95 the elements 10 and 11 are shifted to gripping position with respect to the pipe 38 is shown in Figure 4.

100 The inner face of the intermediate portion 28, of the element 11, is provided with a socket 39, and fixedly engaging therewith is the threaded shank 40 of a spring controlled connecting element which is employed for detachably connecting the element 11 to the element 10.

105 The spring controlled connecting element, not only includes the shank 40, but further a coiled spring 41, which is mounted on the shank 40 between a shiftable retainer 42 and the head 43 of the shank 40.

110 The shank 40 of the connecting element is of a length so that it will project into the chamber 25, of the element 10, and said shank 40 is positioned in the slot 26. The retaining member 42, spring 41 and head 43 are arranged in the chamber 25, and the opening 27 provides means whereby the connecting element can be secured in position with respect to the elements 10 and 11.

115 When the element 11 is shifted lengthwise, relative to the element 10, so that said elements 10 and 11 will assume the position shown in Figure 4, the shifting of the element 11 is had against the action of the spring 41, so that when the element 11 is 120

released the spring 41 will tend to cause the element 11 to assume the position shown in Figure 3.

Threadably engaging with the member 20 5 is a coupling member 44, to which a cable 45' is connected, and threadably engaging with the member 33 is a coupling member 45 to which a cable 46 is connected. The coupling member 44 and cable 45' provide 10 a lifting element for the gripper element 10, and the coupling member 45 and cable 46 provide a lifting element for the gripper element 11.

The lower portion 29 of the gripper element 11, is inset in such a manner as to provide for the seating of the lower terminus of the intermediate portion 28, of the element 11, on the shoulder 17, when the device is in 15 inoperative position, as shown in Figures 20 1, 2 and 3.

The taper of the upper portions 13 and 30, of the elements 10 and 11 respectively, is such that a space, as indicated at 47 will be formed between said portions 13 and 30 25 so that the shifting of the element 11, relative to the element 10, will not be interfered with.

In the modified form shown in Figures 30 11, 12 and 13, the gripper element which constitutes the carrier, and is indicated by the reference character 48, is of the same construction as the element 10, and the reference characters employed in connection with element 10 are used for the details of 35 construction of the element 48. The difference in construction between the device shown in Figure 11, and that shown in Figure 3 resides solely in the construction of the shiftable gripper element 49, and in 40 this connection it will be stated that the gripper element 49 corresponds to the gripper element 11. The element 49 is not provided with the cavities 34 and 35, but in lieu thereof, is formed with a pair of wedge 45 shaped protuberances 50, 51, which cooperate with the inner walls 24, of the cavities 21, 22, for the purpose of shifting the gripper elements 48, 49 laterally and relatively to each other so that the said elements will 50 be moved into gripping engagement with respect to the pipe. Otherwise than that as stated, the construction shown in Figure 11 is the same as that shown in Figure 3.

Although the preferred embodiment of 55 the invention is as illustrated and described, yet it is to be understood that changes in the details of construction can be had which will fall within the light of the invention as claimed.

60 What I claim is:—

1. A pipe puller comprising a pair of interengaging gripper elements, one shiftable lengthwise relatively to the other, a spring controlled connecting element between said gripper elements, a lifting element con-

nected to the upper end of each of said gripper elements, and means for moving said gripper elements laterally with respect to each other when one of said elements is shifted lengthwise relatively to the other. 70

2. A pipe puller comprising a pair of interengaging gripper elements, one shiftable lengthwise relatively to the other, a spring controlled connecting element between said gripper elements, a lifting element connected 75 to the upper end of each of said gripper elements, a plurality of shifting members interposed between said gripper elements, and said gripper elements having means co-acting with said members for shifting the gripper elements laterally with respect to each other when one of the gripper elements is shifted lengthwise relatively to the other. 80

3. A pipe puller comprising a pair of interengaging gripper elements, a spring controlled connecting element between said gripper elements, said connecting element carried by one of said gripper elements and shiftable lengthwise of the other of said gripper elements, a lifting element connected 90 to the upper end of each of said gripper elements, and means arranged between said gripper elements for shifting them laterally relative to each other when one of said gripper elements is shifted lengthwise relatively to the other. 95

4. A pipe puller comprising a pair of interengaging gripper elements, a connecting element between said gripper elements, said connecting element carried by one of said gripper elements and shiftable lengthwise of the other of said gripper elements, and means arranged between said gripper elements for shifting them laterally relative to each other when one of said gripper elements is shifted lengthwise relative to the other. 100

5. A pipe puller comprising a pair of interengaging gripper elements, a connecting element between said gripper elements, said 110 connecting element carried by one of said gripper elements and shiftable lengthwise of the other of said gripper elements, means arranged between said gripper elements for shifting them laterally relative to each other when one of said gripper elements is shifted lengthwise relative to the other, and a lifting element connected to the upper end of each of said gripper elements. 115

6. A pipe puller comprising a pair of interengaging gripper elements, one opposing the other, each of said elements having its inner face provided with a plurality of wedge shaped cavities, the cavities of one of said elements opposing the cavities of the other of said elements and oppositely disposed with respect thereto, and rollers mounted in said cavities and cooperating with the inner walls thereof for shifting the gripper elements laterally with respect to 120

125

130

each other when one of said elements is shifted lengthwise with respect to the other.

7. A pipe puller comprising a pair of interengaging gripper elements, one opposing the other, each of said elements having its inner face provided with a plurality of wedge shaped cavities, the cavities of one of said elements opposing the cavities of the other of said elements and oppositely disposed with respect thereto, rollers mounted in said cavities and cooperating with the inner walls thereof for shifting the gripper elements laterally with respect to each other when one of said elements is shifted lengthwise with respect to the other, and a connecting element secured to one of said gripper elements and extending into and shiftable lengthwise of the other of said elements.

8. A pipe puller comprising a pair of interengaging gripper elements, one opposing the other, each of said elements having its inner face provided with a plurality of wedge shaped cavities, the cavities of one of said elements opposing the cavities of the other of said elements and oppositely disposed with respect thereto, rollers mounted in said cavities and cooperating with the inner walls thereof for shifting the gripper elements laterally with respect to each other when one of said elements is shifted lengthwise with respect to the other, and a spring controlled connecting element secured to one of the gripper elements and extending into and movable lengthwise of the other of said gripper elements.

9. A pipe puller comprising a pair of interengaging gripper elements, one opposing the other, each of said elements having its inner face provided with a plurality of wedge shaped cavities, the cavities of one of said elements opposing the cavities of the other of said elements and oppositely disposed with respect thereto, rollers mounted in said cavities and cooperating with the inner walls thereof for shifting the gripper elements laterally with respect to each other when one of said elements is shifted lengthwise with respect to the other, and a lifting element connected to the upper end of each of said gripper elements.

10. A pipe puller comprising a pair of interengaging gripper elements, one opposing the other, each of said elements having its inner face provided with a plurality of wedge shaped cavities, the cavities of one of said elements opposing the cavities of the other of said elements and oppositely disposed with respect thereto, rollers mounted in said cavities and cooperating with the inner walls thereof for shifting the gripper elements laterally with respect to each other where one of said elements is shifted lengthwise with respect to the other, a connecting element secured to one of said gripper elements and extending into and shiftable

lengthwise of the other of said elements, and a lifting element connected to the upper end of each said gripper elements.

11. A pipe puller comprising a pair of interengaging gripper elements, one opposing the other, each of said elements having its inner face provided with a plurality of wedge shaped cavities, the cavities of one of said elements opposing the cavities of the other of said elements and oppositely disposed with respect thereto, rollers mounted in said cavities and cooperating with the inner walls thereof for shifting the gripper elements laterally with respect to each other when one of said elements is shifted lengthwise with respect to the other, a spring controlled connecting element secured to one of the gripper elements and extending into and movable lengthwise of the other of said gripper elements.

12. A pipe puller comprising a pair of interengaging gripper elements, one opposing the other, each of said elements having its inner face provided with a plurality of wedge shaped cavities, the cavities of one of said elements opposing the cavities of the other of said elements and oppositely disposed with respect thereto, and rollers mounted in said cavities and cooperating with the inner walls thereof for shifting the gripper elements laterally with respect to each other when one of said elements is shifted lengthwise with respect to the other, each of said elements formed with a semi-circular intermediate portion and tapered upper and lower portions, said upper portions of said gripper elements being permanently spaced from each other.

13. A pipe puller comprising a pair of interengaging gripper elements, one opposing the other, each of said elements having its inner face provided with a plurality of wedge shaped cavities, the cavities of one of said elements opposing the cavities of the other of said elements and oppositely disposed with respect thereto, rollers mounted in said cavities and cooperating with the inner walls thereof for shifting the gripper elements laterally with respect to each other when one of said elements is shifted lengthwise with respect to the other, each of said elements formed with a semi-circular intermediate portion and tapered upper and lower portions, said upper portions of said gripper elements being permanently spaced from each other, and a lifting element connected to the upper portion of each of said gripper elements.

14. A pipe puller comprising a pair of interengaging gripper elements, one opposing the other, each of said elements having its inner face provided with a plurality of wedge shaped cavities, the cavities of one of

said elements opposing the cavities of the other of said elements and oppositely disposed with respect thereto, rollers mounted in said cavities and cooperating with the inner walls thereof for shifting the gripper elements laterally with respect to each other when one of said elements is shifted lengthwise with respect to the other, each of said elements formed with a semi-circular intermediate portion and tapered upper and lower portions, said upper portions of said

gripper elements being permanently spaced from each other, a lifting element connected to the upper portion of each of said gripper elements, and a connecting element secured to one of said gripper elements and slidably connected with the other of said gripper elements. 15

In testimony whereof, I affix my signature hereto.

CHARLES H. HUTTO.
